(57) **CLAIM**

The ornamental design for a “portable socket,” as shown and described.

DESCRIPTION

FIG. 1 is a perspective view of a “portable socket” showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the practical usage.

The broken lines throughout the drawings are included for the purpose of illustrating portions of the elements that do not form part of the claimed design, such as Outlet, USB, cell Phone and Cable.

1 Claim, 5 Drawing Sheets
